INKING PAD

Filed Dec. 2, 1921

Inventor:
Frederick H. Bronner

J. J. Heisler Attn.
b6

UNITED STATES PATENT OFFICE.

FREDERICK H. BRONNER, OF PORTLAND, OREGON, ASSIGNOR TO IRWIN-HODSON CO., OF PORTLAND, OREGON.

INKING PAD.

Application filed December 2, 1921. Serial No. 519,404.

To all whom it may concern:

Be it known that I, FREDERICK H. BRONNER, a citizen of the United States, and a resident of the city of Portland, county of Multnomah, and State of Oregon, have invented a certain new and useful Improvement in Inking Pads, of which the following is a specification.

The object of my invention is to provide an improved self-feeding inking pad for rubber stamps and the like, and particularly to improve the device secured to me by Letters Patent of the United States #1,321,785 issued November 11, 1919.

15 It was found that the gelatinous base provided in said device spread and did not stand up under continuous use, and besides the device was not so constructed that the worn parts thereof could be readily removed and replaced.

20 In my present invention I have overcome these defects by encompassing the gelatinous base by a wall of material of lesser resiliency and encompassing such wall by 25 a band-like metal shell.

Furthermore, my improved device is so contrived as to insure the spreading of the ink throughout the disk of absorbent material and prevent that portion of such disk 30 lying directly over the reservoir from becoming saturated with ink. Furthermore, I encompass the circumference of the absorbent disk with a wall of non-absorbent material preferably constituting an integral part of the body of the inking pad, so 35 that the ink will not ooze out over the circumference surface of the pad and thus soil the fingers of the user.

Furthermore, I so arrange the parts of 40 my improved inking pad, that the bottom or gripping surface of the gelatinous pad will extend below the bottom edge of said wall of lesser resiliency, in that way leaving the bottom portion of the gelatinous pad unrestrained so that it may exert a firm grip 45 on the supporting surface without any danger of injuring the latter surface.

The foregoing and incidental features of 50 my invention are hereinafter fully described and illustrated in the accompanying drawings, in which:

Fig. 1 is a plan view of my device with the cover removed, and parts broken away;

Fig. 2 is a side elevation of the same showing cover in section; 55

Fig. 3 is a cross sectional view taken on the line 3—3 of Fig. 1;

Fig. 4 is a cross sectional view of the metal shell of my pad taken on the line 4—4 of Fig. 1; 60

Fig. 5 is a plan view of the skeleton body of my pad;

Fig. 6 is a plan view of the perforated metal disk which prevents the absorbent layer from becoming sagged and also serves 65 the purpose of distributing ink more evenly across the surface of the pad than heretofore; and

Fig. 7 is a sectionalized detail view of the cover and the metal shell of the base, and 70 illustrates the loose fit of the cover on the top of my pad.

I have provided a skeleton rubber body *a* which gives a rigidity to the pad and forms the frame work for all of the parts. 75

The skeleton body consists of a web *a'* having an integral pendent flange-like wall *a''*, the latter being the portion encompassing the circumference of the gelatinous base *e*. Another flange-like wall *a'''* projects above 80 the web *a'*. The skeleton body is contained in band like metal shell *c* preferably made of aluminum. This shell is secured in place on the pendent wall *a''* of the body by providing the latter with locking lugs *b* adapted to project through holes *c'* provided in the shell *c*. 85

The shell *c* extends to the top of the upper wall *a'''* of the skeleton body so as to support such upper wall, but does not extend quite to the bottom of the lower wall *a''* of the skeleton body; and the bottom portion 90 of the gelatinous base projects below the bottom edge of the skeleton body. In this way is assured sufficient stability to the base, at the same time leaving its supporting bottom face amply yielding to assure a firm grip on the desk or other supporting surface, and further insuring that the latter will not be scratched or marred. 95

Within the upper wall *a'''* of the skeleton body *a* is placed a disk of absorbent material *k*. The center of the skeleton body is provided with an ink reservoir or chamber *h* consisting of an annular wall projecting downward from the center portion of the 100 lower side of the web *a'*; the ink chamber *h* 105

is open at both ends, its lower end being closed by a plug *g*. The upper face of the web *a'* of the body is provided with distributing channels *f* radiating from the ink chamber *g*. In order to insure the better distribution of the ink, and prevent the central portion of the absorbent disk *k* from becoming saturated with the ink, a metal disk *j* of the construction shown in Fig. 6 is placed 5 between the web of the body and the disk *k*. As more clearly shown in Fig. 6 the center of this metal disk *j* is solid, and it has radially disposed perforations *j'* from points equi-distant from the center to the edge. 10 It is to be noted that the circumference of the skeleton body at the top is contracted, and the upper portion *m* of the shell inclines inward; in other words provides a sloping exterior surface on which the cover *i* rests. 15 Such construction gives the cover a loose fit, and renders it easy to remove.

The upper surface of the absorbent pad *k* is covered as usual with closely woven silk or similar fabric.

20 The composition of which the base *e* is made may be the same as that described in my previous patent. The composition is heated and poured into the bottom cavity of the skeleton body with the latter inverted. 25 To insure firm adhesion between the skeleton body and the gelatinous base, the web *a'* of the former may be provided with holes *d* into which the gelatinous mass will flow and thus form locking studs *e'* on the upper part 30 of the base. See Fig. 3.

The metallic shell is easily removable and thus affords a means whereby the pad can be recovered or the separate parts renewed without discarding the entire pad. It also 40 provides a means whereby the separate parts of the pad can be replaced as often as necessary with a minimum amount of cost and annoyance.

I claim:

45 1. An inking pad, consisting of a skeleton body made of flexible material which is impervious to ink and provided with a recess for an ink reservoir, said skeleton body being filled with a gelatinous material which 50 forms the base for the pad, and which is keyed to said body.

55 2. An inking pad, consisting of a skeleton body made of rubber which is provided with a recess for an ink reservoir, said skeleton body to be filled with a gelatinous material which forms the base for the pad, the skeleton body being provided with holes and the upper surface of the gelatinous base being provided with projections extending through such holes, said skeleton body being provided on its upper surface with ink-distributing grooves radiating from said 60 ink-reservoir, a layer of absorbent material which provides the inking surface, and a 65 plug for the ink reservoir.

3. An inking pad comprising, a gelatinous base, a skeleton body consisting of a web having a pendent flange-like wall, and another flange-like wall projecting above the web, said pendent wall encompassing the 70 periphery of said gelatinous base, a band-like shell encompassing said upper and lower wall portions of the skeleton body, means for securing the band-like shell in place on the circumference of the skeleton 75 body, the upper face of the web of the skeleton body being provided with radial ink distributing grooves, the center of said skeleton body being provided with an ink reservoir from which said grooves radiate, 80 a stopper for the ink reservoir, a metal disk resting on the upper surface of the web, such disk being solid at the center and provided with radially disposed perforations extending from points equi-distant from the center to the edge of the disk, a disk of absorbent material seated within the upper wall of the skeleton body, and a cover for the top of the 85 pad.

4. In an inking pad comprising, a gelatinous base, a skeleton body consisting of a web having a pendent flange-like wall, and another flange-like wall projecting above the web, said pendent wall encompassing the 90 periphery of said gelatinous base, a band-like shell encompassing said upper and lower wall portions of the skeleton body, means for securing the band-like shell in place on the circumference of the skeleton body, the upper face of the web of the skeleton body being provided with radial ink distributing grooves, the center of said skeleton body being provided with an ink reservoir from which said grooves radiate, 95 a stopper for the ink reservoir, a metal disk resting on the upper surface of the web, such disk being solid at the center and provided with radially disposed perforations extending from points equi-distant from the center to the edge of the disk, a disk of absorbent material seated within the upper wall of the skeleton body, and a cover for the top of the 100 pad.

5. In an inking pad, a gelatinous base, a flexible skeleton body consisting of a web having peripheral walls one projecting above and the other below the web, the latter wall encompassing the periphery of said 105 gelatinous base.

6. In an inking pad, a gelatinous base, a flexible skeleton body consisting of a web having peripheral walls one projecting above and the other below the web, the latter wall encompassing the periphery of said 110 gelatinous base, but not extending quite to the bottom of the latter.

7. In an inking pad, a gelatinous base, a flexible skeleton body consisting of a web having peripheral walls one projecting 115

above and the other below the web, the latter wall encompassing the periphery of said gelatinous base, a band-like shell encompassing said upper and lower walls of the 5 skeleton body.

8. In an inking pad, a gelatinous base, a flexible skeleton body consisting of a web having peripheral walls one projecting above and the other below the web, the latter wall encompassing the periphery of said gelatinous base, but not extending quite to the bottom of the latter, a band-like shell encompassing said upper and lower walls of the skeleton body, but not extending quite to 10 the bottom of the latter.

9. In an inking pad, a gelatinous base, a flexible skeleton body consisting of a web having peripheral walls one projecting above and the other below the web, the latter wall encompassing the periphery of said gelatinous base, a disk of non-absorbent material provided with perforations extending coincidentally with said ink distributing grooves, but not over said ink reservoir, such disk lying between the web of the skeleton-body and said disk of absorbent material.

10. In an inking pad, a gelatinous base, a flexible skeleton body consisting of a web 25 having peripheral walls one projecting

above and the other below the web, the latter wall encompassing the periphery of said gelatinous base, the upper face of the web of the skeleton body being provided with radial ink distributing grooves, the web of 35 said skeleton body being provided with a central annular portion constituting an ink reservoir communicating with said grooves, a disk of absorbent material seated within the upper wall of the skeleton-body, a disk 40 of non-absorbent material provided with perforations extending coincidentally with said ink distributing grooves, but not over said ink reservoir, such disk lying between the web of the skeleton-body and said disk 45 of absorbent material.

11. In an inking pad, a gelatinous base, a disk of absorbent material, a central ink reservoir for the latter, a web of non-absorbent material between the base and said disk, said web having a hole registering with said ink reservoir and provided with ink distributing grooves on the upper face, and a disk of non-absorbent material provided with perforations extending coincidentally 50 with said ink distributing grooves but not over said ink reservoir, such disk lying between the said web and said disk of absorbent material.

FREDERICK H. BRONNER.
